FLAT LOCKING SLIDER FOR FASTENERS

Davis Marinsky, Bronx, N. Y., assignor to White-hall Patents Corporation, Bronx, N. Y., a corporation of New York

Application January 26, 1939, Serial No. 252,878

7 Claims. (Cl. 24—205.5)

This invention relates to lock sliders for separable fasteners employing stringers, wherein the slider may be retained against movement longitudinally of the stringers with the pull of the slider disposed at either end portion of the slider. More particularly the invention relates to a slider of the character described of what is termed the flat type; that is to say, where upper and lower surfaces of the slider are flat and substantially parallel and wherein the pull is disposed within the boundary of the upper surface of the slider when the slider is in the normal or locked position. The novel features of the invention will be best understood from the following description when taken together with the accompanying drawing, in which certain embodiments of the invention are disclosed, and in which the separate parts are designated by suitable reference characters in each of the views, and in which:

20 Fig. 1 is a plan view of a part of a stringer showing one of my improved sliders thereon with part of the construction broken away and in section.

Fig. 2 is a side view of the structure shown in Fig. 1 with a part shown in a different position, and

Fig. 3 is a section on the line 3—3 of Fig. 2.

In sliders for separable fasteners of the non-locking as well as the locking type, it has been the common practice to provide means on the surface of at least one side wall of the channeled slider body for pivotally, slidably, or otherwise coupling a pull in connection therewith. The result of this has been that sliders have of necessity been constructed of relatively thick bodies, and the pivotal or other coupling means has been objectionable, not only from the standpoint of the added thickness in the entire slider, but also from the standpoint of laundering or pressing various articles of apparel upon which devices of this kind are used. It is the purpose of my invention to construct a slider which will avoid these objectionable features and furthermore which will give other new features and characteristics to the slider, and materially improve the fastener as a whole as more fully hereinafter set forth.

To illustrate one adaptation of the invention, I have shown in the accompanying drawing, portions of two stringers 5, 5a comprising the usual stringer tapes having adjacent enlarged or beaded edges 6, 6a to which are secured, at longitudinal spaced intervals, coupling links or scoops 7, 7a.

At 8 is shown a channeled slider body having top and bottom walls 9 and 10 joined at one end

by a triangular connecting web 11. The bottom wall 10 of the slider is of more or less conventional form and is provided with upwardly extending side flanges 12 which guide the scoops into the wide end portion 13 of the slider and longitudinally through the slider in the operation of coupling the scoops 7, 7a together.

The top wall 9 of the slider differs from the usual top wall in that the normal wide end portion 13a thereof is narrower in width than the 10 end portion 13 whereas the other normal narrow end portion 14 of said wall is wider than the corresponding end portion of the bottom wall 10, so that the outer side edges 15 of the wall 9 are parallel throughout the length thereof except for 15 outwardly protruding camming surfaces 16.

Substituted for the usual flanges of the top wall are enlarged downwardly extending flanged bodies 17. The inner surfaces 18 of said bodies correspond in contour to the inner surfaces of 20 the flanges 12 so as to also aid in guiding the scoops through the slider. However, it will appear upon a consideration of Figs. 1 and 2 of the drawing that the flanged bodies 17 terminate short of the flanges 12, but the wall 9 overlies the 15 wall 10 sufficiently to support and guide the 25 scoops into the diverging channels of the upper end portions of said body, as will readily appear upon a consideration of Fig. 1 of the drawing.

The flanged portions 17 are provided with 30 apertures 19 in direct alignment with the protruding cams 16 to receive the inturned pivot ends 20, 20a of a yoke-shaped finger piece or pull 21. In the construction shown, the end 20a is longer 35 than the end 20 and forms the lock element of 35 the slider, said end being of sufficient length to extend into the channel of the slider when the pull 21 is in the full or dotted line position as shown in Fig. 1. In raising the pull to the position shown in Figs. 2 and 3, the side portions or 40 arms 21a of the pull will engage the cams 16, automatically drawing the pin ends 20, 20a outwardly in the apertures 19 and moving the lock element 20a out of engagement with the links or 45 scoops of one of the stringers; for example, the links 7a in the construction shown. It will of course be apparent that either one of the pins may be the longer pin and form the coupling element. It will also be noted that the pin ends 20a 50 are so mounted in connection with the slider or the portions 1a thereof as to clear the beaded edges 6, 6a of the stringers.

At this point it is well to call attention to the fact that with this construction, it is impossible for the locking element to engage the upper sur-

faces of the links or scoops; that is, when plated, enamelled, or otherwise coated links or scoops are employed, the upper surfaces thereof cannot be marred or otherwise destroyed, and further, no 5 wear can appear on a link or scoop of any type or kind. The term upper surfaces refers to the surfaces of the links or scoops as seen in Fig. 1.

It will also be apparent that the pull 21 is constructed of resilient or springy material so tensioned as to normally assume a position similar to that illustrated in full lines in Fig. 1, capable of outward flexure by engagement of the cams 16 as is illustrated in Fig. 3.

The invention is applicable to metallic type of 15 fasteners of the kind under consideration wherein all of the parts are composed of metal, but is also applicable to fasteners wherein the links or scoops may be composed of plastic materials and further wherein the slider may be composed of 20 plastic materials, and in fact, in using certain plastic materials such for example as cellulose acetate, it is possible to use this material in the construction of the pull, cellulose acetate having 25 sufficient spring properties to produce the desired result.

It will of course be apparent that with a structure of the kind under consideration, the lock element end 20a of the pull operates in the form 30 of a wedge or key, movable transversely with respect to the slider. Any stress or strain on this element is not transmittable to the pull, and thus a positive locking of the slider is provided at all times, and when the slider is strained to move longitudinally of the stringers by a tendency to 35 separate the stringers as is experienced in the use of fastening devices of this kind upon certain articles and garments. It will also appear that the cam portions 16 in addition to operating to release the lock element, also cooperate with the 40 pull to support the same in either the full or dotted line position shown in Fig. 1. In these positions of the pull it will be understood that the upper surfaces of the pull are arranged below the upper or outer surface 9a of the wall 9, so that 45 the pull does not protrude beyond the surface 9a. It will also appear that the contour of the pull 21 is such as to fit over the end 13a of the top wall 9 of the slider as is clearly illustrated in dot and dash lines in Fig. 1 of the drawing.

From the foregoing it will appear that in addition to providing a very simple practical and yet 50 strong and durable form of lock for sliders of the kind under consideration, it is also possible to produce a slider body which will be considerably 55 thinner than the conventional forms of sliders, and thus properly termed a flat slider. The advantage of this construction is that in addition to forming a neat and finished appearance, it also facilitates the laundering, pressing and handling 60 of the device as applied to merchandise of various kinds and classes.

A slider of the kind under consideration adapts 65 itself for use in the conventional locking type of slider as well as what is termed a reverse lock slider, suitable for use on leggings and other articles of apparel and merchandise where the normal wide end portion of the slider hangs downwardly when the fastener is in closed position. In both positions the slider is securely retained 70 against movement on the stringers.

It will also appear that my invention, insofar 75 as the flat slider construction is concerned, is not necessarily restricted for use in connection with lock sliders, in which latter event other forms of pulls may be employed and the camming surfaces

16 may be dispensed with, aside from the desirability of using such surfaces or their equivalents for supporting the pull in either of the positions indicated in Fig. 1.

It will appear that one of the principles of my 5 invention is in the provision of a locking element which is movably supported in the peripheral side edge portion of the slider body to enter the channel thereof so as to engage the links or scoops of at least one stringer where mounted 10 upon the stringer tape, and further to engage side surfaces of the links or scoops below the upper surface thereof, the advantages of the latter structure having been heretofore set forth.

It will of course be apparent that both pivot 15 ends 20, 20a may be of sufficient length to enter the channels so that either of these ends may engage the stringer links 7 or 7a. In a balanced mounting of the pull of course only one pivot end 20 can function. If it be desired to otherwise mount the pull, then both ends can be moved into locking position.

Having fully described my invention, what I 25 claim as new and desire to secure by Letters Patent, is:

1. A slider for separable fastener stringers of the class described, said slider comprising a channeled body having spaced top and bottom walls, the bottom wall having diverging channels at one end bounded by inturned side flanges extending to the other end of said wall, the top wall having at opposite sides thereof enlarged flange portions, inner surfaces of which are in alignment with the inner surfaces of the flanges of said bottom wall for a portion of the length thereof, 30 said top wall having substantially parallel side edges, said wall being of less width than the width of the first named end portion of the bottom wall and of greater width than the other end portion of the bottom wall, the enlarged flange 35 portions of said top wall having apertures arranged in transverse alignment with each other opening outwardly through the side edges of the top wall and into the channel of the slider, a yoke-shaped pull having inwardly extending ends 40 pivotally arranged in said apertures, said pull adjacent the inwardly extending ends thereof being resilient, and said slider having adjacent the apertures therein cam surfaces adapted to flex said ends outwardly in the pivotal movement 45 of said pull into elevated position with respect to said slider.

2. A slider for separable fastener stringers of the class described, said slider comprising a channeled body having spaced top and bottom walls, the bottom wall having diverging channels at one end bounded by inturned side flanges extending to the other end of said wall, the top wall having at opposite sides thereof enlarged flange portions, inner surfaces of which are in 50 alignment with the inner surfaces of the flanges of said bottom wall for a portion of the length thereof, said top wall having substantially parallel side edges, said wall being of less width than the width of the first named end portion of the bottom wall and of greater width than the other end portion of the bottom wall, the enlarged flange 55 portions of said top wall having apertures arranged in transverse alignment with each other opening outwardly through the side edges of the top wall and into the channel of the slider, a yoke-shaped pull having inwardly extending ends 60 pivotally arranged in said apertures, said pull adjacent the inwardly extending ends thereof being resilient, said slider having adjacent the aper- 65

tures therein cam surfaces adapted to flex said ends outwardly in the pivotal movement of said pull into elevated position with respect to said slider, one of the pivot ends of said pull being longer than the other and normally extending into the channel of the slider and adapted to be withdrawn from said channel in the pivotal movement of said pull over said cam surfaces.

3. A slider for separable fastener stringers of the class described, said slider comprising a channeled body having spaced top and bottom walls, the bottom wall having diverging channels at one end bounded by inturned side flanges extending to the other end of said wall, the top wall having at opposite sides thereof enlarged flange portions, inner surfaces of which are in alinement with the inner surfaces of the flanges of said bottom wall for a portion of the length thereof, said top wall having substantially parallel side edges, said wall being of less width than the width of the first named end portion of the bottom wall and of greater width than the other end portion of the bottom wall, the enlarged flange portions of said top wall having apertures arranged in transverse alinement with each other opening outwardly through the side edges of the top wall and into the channel of the slider, a yoke-shaped pull having resilient inwardly extending pivot ends arranged in said apertures, one of said ends extending into the channel of said slider in engaging the links, and said slider having camming means adjacent said last named inwardly extending end of the pull for flexing said resilient end in the pivotal movement of the pull, thereby withdrawing said end from said channel.

4. A slider for separable fastener stringers of the class described, said slider comprising a channeled body having spaced top and bottom walls, the bottom wall having diverging channels at one end bounded by inturned side flanges extending to the other end of said wall, the top wall having at opposite sides thereof enlarged flange portions, inner surfaces of which are in alinement with the inner surfaces of the flanges of said bottom wall for a portion of the length thereof, the enlarged flange portions of said top wall having apertures arranged in transverse alinement with each other opening outwardly through the side edges of the top wall and into the channel of the slider, a yoke-shaped pull having resilient inwardly extending pivot ends arranged in said apertures, one of said ends extending into the channel of said slider in engaging the links, said slider having camming means adjacent said last named inwardly extending end of the pull for flexing said resilient end in the pivotal movement of the pull, thereby withdrawing said end from said

channel, and said camming surfaces overlying the pivotal axis to provide for locked arrangement of said long pivot end in the reverse position of said pull.

5. A slider for separable fasteners of the class described comprising a channeled body, said body having intermediate its ends apertures opening through opposite sides of the body and into the channel thereof, side edges of the body adjacent the apertures having outwardly protruding cam surfaces, a yoke-shaped pull having inwardly set pivot ends arranged in said apertures, and the pull having spring properties normally supporting said ends in inwardly extended position with at least one of said ends protruding into the channel of the slider to form a lock element controlling movement of the slider when the pull is arranged substantially in horizontal position with respect to the slider, whereby in the upward swinging pivotal movement of the pull said cam surfaces will yieldably withdraw the lock element from the channel of the slider.

6. A lock slider for separable fastener stringers of the class described comprising a channeled body movable along the stringers to couple and uncouple the same, said body having flanged side edges, a resilient lock element pivotally supported in connection with the slider and having at least one part supported in an aperture in one of said flanged edges and movable transversely of the slider to extend into the channel thereof in a direction substantially at right angles to the movement of the stringers through said channel, said element yieldably supporting said part in position extending into the channel of the slider, and means on the slider associated and cooperating with said element for withdrawing said part from the channel in swinging said element on the slider.

7. The combination with a channeled slider body for separable fastener stringers having apertures in opposed side portions of the body and opening into the channel thereof, of a yoke-shaped pull having spring arms terminating in inwardly extended pivot ends arranged in the apertures of said slider and normally held in inwardly extended positions by the resilient properties of said pull to normally extend at least one of said pivot ends into the channel of the slider to form a lock element, and said slider having a cam surface adjacent the pivot end of the pull and cooperating with the arm supporting said lock element whereby in pivotal movement of the pull into raised position on the slider the arm will engage said cam surface to withdraw the lock element from the channel of the slider.

DAVIS MARINSKY.
